UNITED STATES PATENT OFFICE.

JOHN T. HAYNE, OF DETROIT, MICHIGAN.

DESIGN FOR A RUNNING-BOARD FOR AUTOMOBILES.

53,736.

Specification for Design.

Patented Aug. 26, 1919.

Application filed March 31, 1919. Serial No. 286,575. Term of patent 14 years.

To all whom it may concern:

Be it known that I, JOHN T. HAYNE, residing at Detroit, in the county of Wayne and State of Michigan, have invented a new, original, and ornamental Design for a Running-Board for Automobiles, of which the following is a specification, reference being had to the accompanying drawings, forming part thereof.

Figure 1 is a perspective of a running board showing my new tread surface design.

Fig. 2 is a cross section taken on the dotted line A—A Fig. 1.

I claim:

The ornamental design for a running board for automobiles, as shown.

March 29th, 1919.

JOHN T. HAYNE.

Witnesses:

J. Ross COLHOUN,
C. T. BELT.
